CLOTHES RACK

J. Lynn McCormick, Indianapolis, Ind.

Application July 19, 1945, Serial No. 605,886

4 Claims. (Cl. 312—300)

1

This invention relates to a drying rack.

The chief object of this invention is to provide a drying rack which, if desired, may be of portable and of enclosed type with rack elements positively retainable in the collapsed or drying positions and by mechanism of exceptional simplicity.

Another object of this invention is to provide such a rack with a cushion device to cushion the movement of the rack elements in one direction.

The chief feature of the present invention resides in the rack element or bar supporting means, its support, and the means associated therewith for normally constraining the bars towards drying position and the lock for holding same therein.

A further feature of the invention resides in the dashpot cushion effective when the bars approach the drying position for bar movement slowdown to permit automatic locking.

Another feature of the invention resides in the manual control for the aforesaid means.

Other objects and features of the invention will be set forth more fully hereinafter.

The full nature of the invention will be understood from the accompanying drawings and the following description and claims.

In the drawings

Fig. 1 is a longitudinal vertical sectional view through one embodiment (and of cabinet type) of the invention, the drying bars being shown extended or in drying position, the door of the cabinet being broken away and open.

Fig. 2 is a similar view of the invention, the bars being shown in collapsed position and the cabinet door being shown in closed position.

Fig. 3 is a rear elevational view of the supported ends of the rack bars, and immediately associated support and control means.

Fig. 4 is an elevational view of the upper end of the manual control member and mechanism immediately associated therewith.

In the drawings 10 indicates the back wall of a cabinet having sides 11, top 12, bottom 13 and front 14, the latter providing an opening 15 closable by door means 16 of the desired type. Such a cabinet can be secured to a wall by any suitable means or detachably suspended from wall supports as desired and by suitable means not shown but operatively associated with the cabinet at 17, see Fig. 3.

Secured within the cabinet is a pair of spaced vertical rails 18 and near the top thereof and pivotally mounted therein is shaft 19, which at

2

one end 20 (herein to the right Fig. 3) projects towards the side 11 and mounts at 39 cam member 21 between rail 18 and side 11.

Pinned as at 22, or otherwise suitably secured to the cam, is a flexible member or cord 23 (same may be metallic), which also is connected to spring 24 having its lower end secured at 25 to rail 18. Thus shaft 19 is always constrained to clockwise rotation, see Fig. 2.

Rigid with shaft 19 and between rails 18 is a tiltable base having an upper plate 26, a spacing portion 27 and a lower plate 28, the latter projecting beyond plate 26. Between the plates 26—28 and on parallel spaced pivots 29, arcuately arranged, are pivotally mounted drying bars 30. These bars normally hang down, see Fig. 2, and when the base is released it is tilted clockwise and the bars are projected outwardly, as shown in Fig. 1, and when so projected the bars 30 may be moved laterally as desired or required for radial spacing, as it were.

To cushion the projection of the bars there is provided a dashpot structure comprising a cylinder 31 carried by bracket 32 pivoted at 33 on rail 18. In said cylinder is dashpot piston 34 carried by rod 35. Same at its other end terminates in eye 36 and same is accommodated and confined by groove 37 in cam 21 and anchored by pin 38. Pin 39 anchors the cam to shaft 19, all as shown in Fig. 3.

As shown in Figs. 2 and 3, plate 26 projects upwardly beyond portions 27 and 28 when the rods are lowered and cabinet closed. As shown in Fig. 2, a stop pin member 40 normally lies behind the upward projection aforesaid and serves to hold the base and bars in the collapsed position in opposition to the constraint of spring 24.

Mounted upon back 10 is stop block 41 upon which the plate 26 bears, see Fig. 1, when tilted by spring 24. A third stop is provided to prevent counterclockwise tilting from the extended position and thereby prevent dropping of the clothes, etc., on the bars. Same comprises a roller 42, see Fig. 4, carried by arm 43 pivoted at 44 upon a base plate 45 secured to the back 10.

An arm 46 is pivoted at 46a to said plate and carries the stop pin 40 aforesaid. The arm has pivoted to it at 47 the upper end of manual control rod 48 that extends downwardly and usually terminates below bottom 13. It may, however, otherwise terminate in a cabinet exposed portion or connected means.

Arm 46 is connected by link 48a or the like to arm 43 adjacent roller 42. Spring 49 is connected to the arm 43 in opposition, as it were,

and it is anchored at 50 to plate 45. Thus arm 43 is normally constrained toward counterclockwise rotation, see Fig. 4, but this is limited by the weight of rod 48 and arm 46 for the latter overlies arm 43 at its upper and squared end 51.

Accordingly, until rod 48 is elevated, the pin 40 lies as shown in Figs. 1, 2 and 4. When rod 48 is elevated the spring 24 is effective to tilt the rigidly connected parts 26-27-29 and the bars 30 clockwise, see Fig. 2, to projected or drying position, see Fig. 1. In this rod movement the arm 46 is tilted upwardly and by link 48a the arm 43 is tilted clockwise against spring 49.

When the base and bars are spring elevated, the rod 48 is released and the rod drops by gravity. Spring 49 is then effective, so that arm 43 moves from the dotted line position, see Fig. 4, to the full line position in which position the roller 42 overlies plate 26, see Fig. 1, to hold the base and bars against clothes dropping.

The parts are so arranged that when the bars are collected, as it were, said bars can be tilted downwardly into the cabinet when the base is released from roller stop 42. This is in opposition to spring 24 and the base and bars are then locked in the collapsed position by stop 40 which yields upwardly, see Fig. 4, to pass the base forwardly thereof. Pulling down upon the collected extended bars, with a force sufficient to overcome spring 24, causes lever 43 to tilt clockwise, and effect elevation of lever 46 and pin 40, and will automatically effect base release. However, it is preferred to push up on rod 48 and pull down upon the bars to nest same in the cabinet for in this operation pin 40 is elevated to permit free travel of the base from the position shown in Fig. 1 to that shown in Fig. 2 wherein the pin 40 functions as a stop.

While the invention has been illustrated and described in great detail in the drawing and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. Control mechanism for a clothes rack and like structure including in combination a pivoted arm, a second pivoted arm, the arms normally being disposed substantially transverse to each other, with the exposed end of one arm immediately adjacent the other arm, each of the arms being normally constrained for movement in the same direction of rotation, link means connecting said arms remote from the pivot portions thereof, stop means carried by each of said arms, and manually operable means for at least one of the arms.

2. In a rack structure a bar-supporting pivotally mounted means, means normally constrain-

ing said bar-supporting means in one position, cushion means for limiting the movement of the bar-supporting means into its constrained position, manually releasable means for holding said bar-supporting means in another position in opposition to said constraining means, stop and bearing means positioned to be operatively engaged by the bar-supporting means when the same is released to said constrained position and other stop means engageable with said bar-supporting means for maintaining the bar-supporting means in engagement with the stop and bearing means.

3. In a rack structure a bar-supporting pivotally mounted means, means normally constraining said bar-supporting means in one position, cushion means for limiting the movement of the bar-supporting means into its constrained position, manually releasable means for holding said bar-supporting means in another position in opposition to said constraining means, stop and bearing means positioned to be operatively engaged by the bar-supporting means when the same is released to said constrained position and other stop means engageable with said bar-supporting means for maintaining the bar-supporting means in engagement with the stop and bearing means, and means operatively connecting the manually operable means and the second mentioned stop means for simultaneous operation.

4. In a rack structure a bar-supporting pivotally mounted means, means normally constraining said bar-supporting means in one position, cushion means for limiting the movement of the bar-supporting means into its constrained position, manually releasable means for holding said bar-supporting means in another position in opposition to said constraining means, stop and bearing means positioned to be operatively engaged by the bar-supporting means when the same is released to said constrained position and other stop means engageable with said bar-supporting means for maintaining the bar-supporting means in engagement with the stop and bearing means, and simultaneously and independently operable means operatively connecting the manually operable means and said second mentioned stop means.

J. LYNN McCORMICK.
